UNITED STATES PATENT OFFICE

WILLIAM E. RICH, OF BRADLEY, ARKANSAS, ASSIGNOR OF ONE-HALF TO ROY BRITTON, OF COTTON VALLEY, LOUISIANA

PIPE CLAMP

Application filed October 20, 1930. Serial No. 490,015.

This invention relates to well drilling apparatus employed to clamp and suspend a pipe string within a well casing.

An important object is the provision of an improved, gravity controlled pipe clamp having manual releasing means, and which may be assembled at a well head and be secured in position.

Another object is the provision of a clamp of this character comprising complementary sectional castings adapted to be secured together around a pipe, and in which an element of the clamp releasing means functions as the means for securing the sections in assembled relation.

Other objects will be apparent to those skilled in the art. In this specification and accompanying drawings I have described and illustrated a practical embodiment of the invention, constituting the best means I have thus far devised for reducing the invention to practice.

In the drawings:

Figure 1 is an elevation of a clamp constructed in accordance with the invention, as applied in service.

Figure 2 is a top plan view thereof.

Figure 3 is a vertical section on line 3—3 of Figure 2, with parts in elevation.

Figure 4 is a horizontal section on line 4—4 of Figure 1.

Figure 5 is substantially a vertical section on line 5—5 of Figure 2.

Figure 6 is a top plan view of the clamp in open position.

Figure 7 is a top plan view of a clamp release element.

Figure 8 is a fragmentary perspective of a portion of the element shown in Figure 7.

In detail the clamp consists of a pair of complementary semi-circular casting sections 10 and 11, the walls of which are laterally inturned at their upper ends to form arcuate tops 12 and 13 having each a semi-circular recess. On the respective section

tops an integral upstanding guide lip 14, 15, is formed at the edge of the recess and with the sections 10 and 11 assembled as shown best in Figure 2, the diameter of the bore formed by the top recesses is sufficiently large to provide ample clearance for a pipe string to be passed through the clamp.

The lower end of the clamp is formed with reduced neck portions 16 and 17 for proper seating engagement in a well casing head, 55 not shown, and above the lower end but appreciably below the horizontal median of the clamp, the section walls 10 and 11 have integral, internal annular shoulders 18 and 19, each having a flat upper face and being provided with a semi-circular recess corresponding in dimensions to the recesses in the tops 12 and 13 which they underlie.

The casting sections 10 and 11 are coupled in hinged relation by means of a pintle 20 passed downwardly through upper and lower sets of overlapping ears 21 and 22 extending laterally from the respective castings 10 and 11 and being integral therewith, and the pintle is provided at its upper end 60 with an eye head 23 for seating and lifting purposes. The ears 21 and 22 are so arranged that the pivot of the hinge coupling between the sections is disposed in line with the joint between the sections when in assembled position.

Diametrically opposite the ears 21 and 22 with respect to the sections when assembled in service position, are identical sets of ears 24 and 25 on the casting sections 10 and 11 respectively. These ears are also apertured and overlap, receiving therethrough the shank of a standard 26 having its upper end formed with an enlarged fork 27 between the arm of which is pivoted a rocking lever 28 having a bifurcated end forming curved arms 29 and 30 which extend over the section tops 12 and 13, the terminals of the arms being engageable through eyes 31 80

and 32 provided at the upper ends of a pair of lift rods 33 and 34.

These lift rods are mounted for vertical reciprocation in the respective sections, being guided through the tops 12 and 13 and the shoulders 18 and 19. The rod 33, above the shoulder 18, is threaded for a portion of its length to receive a pair of lock nuts 35 which are adapted to clamp between them selves a horizontally disposed arcuate lift ring section 36 having its ends formed with tongues 37 which, when the sections 10 and 11 are brought into assembled position, engage in grooves 38 formed in the ends of a similar lift ring section 39 clamped between lock nuts 40 threaded on lift rod 34. It is obvious that through manipulation of the nuts 35 and 40 the ring sections 36 and 39 may be adjusted longitudinally of the rods 33 and 34 to insure proper engagement of their tongue and groove end connections.

The casting section 10 has integrally formed in its walls a pair of spaced radial outwardly extending housings 41 through the sides of which are disposed pivot pins 42 forming the fulcrums for the outer ends of vertically oscillatable links 43 which extend radially inward of the casting section and which have pivotal connection at their inner ends, by means of pivot pins 44, with pipe engaging dogs 45.

In like manner the casting section 11 has formed therein the housings 46, pivot pins 47, links 48, pivots 49 and holding dogs 50, corresponding in number and disposition to the identical elements in the section 10.

In operation, assuming the casting section to be coupled in assembled service position as shown in Figure 1, the lever 28 is rocked on its fulcrum to elevate the arms 29 and 30, which through their engagement in the lift rod eyes 31 and 32 will cause a corresponding lifting movement of the rods 33 and 34. This movement of the lift rods elevates the lift ring comprising the sections 36 and 39 which in turn engage under the inner ends of the links 43 and 48 thus lifting the pipe clutch dogs 45 and 50 through a vertical arc which causes, in effect, a retraction of the pipe dogs relative to the axis of the clamp. It is apparent that under such retraction the pipe dogs mutually separate sufficiently to permit free passage of a pipe through the clamp.

In pipe engaging position, the lever 28 is rocked to depress the arms 29 and 30, rods 33 and 34 and ring sections 36 and 39. The dogs 45 and 50 are thus freed to fall against the pipe 51, jamming their serrated engaging faces against the pipe whereby the same is held against downward movement in a manner well known to the art.

While in this embodiment of the invention I have shown and described certain details entering into the construction and oper-

ation thereof, I desire it to be understood that the same do not constitute limitations, but that any desired changes may be made in such details as will fall within the scope of the invention as claimed.

I claim:

1. In a pipe clamp, a casing, links mounted therein for vertical swinging movement, pipe clutch dogs carried by said links, lift rods vertically slideable in said casing, link engageable means secured on said rods and adjustable longitudinally thereof, and means for moving said lift rods vertically in the casing.

2. A pipe clamp comprising a casing adapted for assembly around a pipe, pipe engaging dogs carried by said casing, lift rods mounted in said casing for vertical movement, means carried by said lift rods and adapted to elevate said dogs on lifting movement of said rods, and a lever fulcrumed on said casing externally thereof and operatively engageable with said rods.

3. A pipe clamp comprising separable sections, means for securing said sections in assembled relation around a pipe, radially disposed links pivoted in the walls of said sections, pipe clutch dogs on the inner ends of said links, means for engaging the under sides of said links simultaneously to lift the same and dispose said clutch dogs in inoperative position, and means having fixed connection within said sections with said link engaging means for operating the same.

4. A pipe clamp comprising a casing, pipe engaging members mounted therein for vertical swinging movement, means in said casing for slidably engaging said members from beneath and having no connection therewith, and means having a positive connection with said member engaging means within the confines of the casing for elevating said member engaging means.

5. A pipe clamp comprising a casing, pipe holding means in said casing and movable to pipe engaging position, and manually operable means supported in said casing out of contact with the walls thereof beneath said holding means for applying lifting force thereto.

6. In a pipe clamp, a casing, radially disposed pipe engaging elements mounted therein for vertical swinging movement, a lift rod disposed in the casing for vertical reciprocation, and a member extending within the casing beneath said pipe engaging elements and slidably abutting the same, said member being attached to said lift rod and being vertically adjustable thereon.

7. A pipe clamp comprising a casing, links mounted therein for vertical swinging movement, pipe clutch dogs carried by said links, a lift rod vertically slideable in bearings provided in said casing, and means attached to said lift rod in free sliding engagement

against the under faces of said links for applying lifting force thereto.

8. A pipe clamp comprising a casing provided with a bore to receive a pipe therethrough, pipe engaging dogs housed within said casing and pivotally mounted therein, said dogs having a normal bias to pipe engaging position, means housed within said casing for moving said dogs to pipe disengaged position, clamp operating means externally of the casing and including means extending through a wall of the casing and connected to said pipe dog moving means.

In testimony whereof I affix my signature.
